UNITED STATES PATENT OFFICE.

JOHN STUTIKA, OF WEST PULLMAN, ILLINOIS.

ATTACHMENT FOR INTERNAL-COMBUSTION ENGINES.

Application filed June 26, 1922. Serial No. 570,879.

To all whom it may concern:

Be it known that I, JOHN STUTIKA, a citizen of the United States, residing at West Pullman, in the county of Cook and State of Illinois, have invented certain new and useful Improvements in Attachments for Internal-Combustion Engines, of which the following is a specification.

This invention relates to devices for modifying the combustible charges of internal combustion engines and for supplying additional combustible charges when desired.

The device comprises a valve casing having a pipe connected to a source of water vapor such as the radiator of an automobile, a pipe connected to the intake manifold, and a pipe connected with an auxiliary gasoline tank mounted adjacent the carburetor of the automobile, means being provided and controlled by the spark rod of the automobile for feeding moisture, moisture and combustible charges, or combustible charges alone to the intake manifold of the engine.

An important object of the invention is the provision of a valve of the above mentioned character automatically controlled by the spark rod of the automobile for selectively admitting moisture or combustible charges or both to the intake manifold of the engine.

Other objects and advantages of the invention will be apparent during the course of the following description.

In the drawings, I have shown one embodiment of the invention. In this showing,

Figure 1 is a side elevation of a portion of the automobile, showing the attachment in place thereon,

Figure 2 is a detail sectional view through the valve taken on line 2-2 of Figure 1,

Figure 3 is a plan view of the valve and associated elements,

Figure 4 is an end elevation of the same,

Figure 5 is a diagrammatic sectional view showing one position of the valve within the casing,

Figure 6 is a similar view showing a second position of the valve,

Figure 7 is a similar view showing a third position of the valve,

Figure 8 is a similar view showing a fourth position of the valve, and,

Figure 9 is a detail elevation showing the

auxiliary gasoline tank and associated elements, parts being shown in section for the purpose of illustration.

In the drawings, the numeral 10 designates an automobile provided with a frame 11 having the usual engine 12 mounted thereon and provided with an intake manifold 13. The automobile is provided with the usual steering column 14 and steering wheel 15. A spark control rod 16 is mounted adjacent the steering column and adapted to be controlled by the usual spark lever 17. The combustible charge for the engine is provided for through the usual carburetor 18 while the usual engine cooling apparatus is employed including a radiator 19. As usual the radiator 19 is provided with an overflow pipe 20.

The numeral 21 designates a valve casing preferably mounted, as shown in Figure 1, and this valve casing is provided with an inlet port 22 and an outlet port 23, these ports communicating respectively with the interior of the casing through the medium of relatively long narrow passages 24 and 25.

A valve body 26 is mounted within the valve casing and is preferably tapered and provided with an internal bore 27. A nipple 28 is screw-threaded into the larger end of the valve casing and a spring 29 is mounted between the inner end of the nipple 28 and the larger end of the valve body whereby the latter is made to fit tightly within the valve casing. The smaller end of the valve body is provided with a screw-threaded opening for the reception of a screw-threaded stem 30 having an operating handle 31. This stem has its inner end projecting within the bore 27 of the valve and is provided externally of the valve with a lock nut 32 for a purpose to be described. The valve is provided with a series of relatively large openings 33, preferably three in number and a single smaller opening 34 adjacent the openings 33, these openings being adapted successively to register with the passage 25. The lower portion of the valve is provided with a series of small openings 35, preferably two in number, and a pair of larger openings 36, these openings being adapted successively to register with the passage 24.

As shown in Figure 3, the valve body is provided adjacent the smaller end with

steam. It will be apparent also that a small quantity of additional air will be drawn into the manifold through the small opening 57 in the nipple 28. When running at exceptionally high speeds where a further advanced spark is desirable and a slightly greater amount of combustible fuel is necessary, the valve 26 will be advanced to the position shown in Figure 6 in which the openings 33 communicate as before with the intake manifold while the small openings 35 afford communication with the auxiliary tank 61. Since the area of the openings 35 is materially less than that of the openings 33, a partial vacuum will be maintained in the valve 26, to hold the valve 44 in open position. In this position of the valve it will be apparent that both water vapor and additional air will be supplied to the engine as well as an additional combustible charge. When the engine is not running the spark may be further advanced to place the valve 26 in the position shown in Figure 5 when all the ports will be closed.

During days when sufficient water vapor is present in the atmosphere to supply the normal needs of the engine, the cap 55 may be revolved to one-half a revolution to close the opening 56. Under this condition moisture will pass into the engine through the air intake of the carburetor and also through the small opening 57 of the nipple 28. In connection with the opening 57 it is noted that when the engine is not in operation, any water of condensation forming in the pipe 53 will be drained out through this opening.

Tension of the spring 51 against the valve 44 may be regulated to adjust the amount of water vapor drawn through the valve by loosening the jam nut 32 and adjusting the stem 30 inwardly or outwardly to vary the position of the plug 50, and the nut 32 again tightened to lock the stem 30 against movement.

As is well known, carburetors employed in internal combustion engines often flood during the normal operation of the engine and more particularly when starting, causing a loss of combustible fuel. In the present construction I provide the auxiliary tank 61 mounted beneath the float chamber of the carburetor to catch the waste due to the flooding of the carburetor. As shown in Figure 9, the arrangement of the head 63 of the tank 61 forms a basin to catch the drippings from the carburetor, the fuel caught in this basin passing into the tank 61 through the opening 64. If it is found that insufficient combustible fuel is supplied to the tank 61 through the means above stated, the pet cock of the carburetor may be opened to supply additional gasoline.

The arrangement of the elongated passages 24 and 25 allows for the arrangement in alignment of the relatively large openings

of the valve 26 whereby a substantial area of these openings is obtained, while at the same time relatively slight movements of the valve 26 place the various openings of the valve 26 in or out of registration with these passages. 70

It is to be understood that the form of my invention herewith shown and described is to be taken as a preferred example of the same, and that various changes in the shape, 75 size, and arrangement of parts may be resorted to without departing from the spirit of the invention or the scope of the subjoined claims.

Having described my invention, I claim: 80

1. The combination with an internal combustion engine having an intake manifold, of a valve casing, an auxiliary gasoline tank, means for connecting said tank to said valve casing, a pipe for connecting said valve casing to a source of water supply, a check valve arranged in said pipe, means for normally closing said check valve, a conduit for connecting said valve casing to the intake manifold of the engine, a control valve 85 arranged in said valve casing, said control valve being provided with openings of varying sizes, and means for operating said control valve. 90

2. The combination with an internal combustion engine having an intake manifold and a spark control rod, of a valve casing, an auxiliary gasoline tank, means for connecting said tank to said valve casing, a pipe for connecting said valve casing to a 100 source of water supply, a check valve arranged in said pipe, means for normally closing said check valve, a conduit for connecting said valve casing to the intake manifold of the engine, a control valve arranged 105 in said valve casing, said control valve being provided with openings adapted to communicate with said auxiliary tank and the intake manifold of the engine, and means connected between said control valve and 110 the spark control rod of the engine for operating said control valve. 115

3. The combination with an internal combustion engine having an intake manifold, of a valve casing, said valve casing being 115 provided in its sides with an inlet port and an outlet port, said valve casing being further provided with elongated passages arranged longitudinally of said valve casing to afford communication between said ports and the 120 interior of said valve casing, an auxiliary gasoline tank, means for connecting said tank to said inlet port, a pipe for connecting said valve casing to a source of water vapor supply, a conduit for connecting said 125 outlet port to the intake manifold of the engine, a check valve arranged in said pipe, means for normally closing said check valve, a control valve arranged in said valve casing, said control valve being provided with 130

openings adapted to selectively register with said elongated passages, and means for operating said control valve.

4. The combination with an internal combustion engine having an intake manifold and a spark control rod, of a valve casing, a pipe for connecting said valve casing to a source of water vapor supply, a conduit for connecting said valve casing to the intake manifold of the engine, a control valve arranged in said valve casing, and means connected between said control valve and the spark control rod of the engine for operating said control valve.
5. The combination with an internal combustion engine having an intake manifold, of a valve casing, said valve casing being provided in its sides with an inlet port and an outlet port, said valve casing being further provided with elongated passages arranged longitudinally of said valve casing to afford communication between said ports and the interior of said valve casing, an auxiliary gasoline tank, means for connecting said tank to said inlet port, a pipe for connecting said valve casing to a source of water vapor supply, a check valve arranged in said pipe, means for normally closing said check valve, a conduit for connecting said outlet port to the intake manifold of the engine, a control valve arranged in said casing, said control valve being provided with longitudinal sets of openings of varying sizes, said sets of openings being

adapted to selectively register with said passages, said check valve being adapted to be opened under normal conditions by the suction of the intake manifold of the engine when said outlet port communicates with the interior of the valve casing and to close when the openings in the valve affording communication between said outlet port and the interior of the valve are smaller than the openings affording communication between said inlet port and the interior of said valve, and means for operating said control valve.

6. The combination with an internal combustion engine having an intake manifold, of a valve casing, an auxiliary fuel tank, means for connecting said tank to said valve casing, a pipe for connecting said valve casing to a source of water vapor supply, a check valve arranged in said pipe, a control valve arranged in said valve casing adjacent and in axial alignment with said check valve, a compression spring arranged between said valves and adapted to normally close said check valve, said control valve being provided with openings of varying sizes, and means for operating said control valve.

In testimony whereof I affix my signature in the presence of two witnesses.

JOHN STUTIKA.
